UNITED STATES PATENT OFFICE.

JOHN B. TYTUS, OF MIDDLETOWN, OHIO, ASSIGNOR TO THE AMERICAN ROLLING MILL COMPANY, OF MIDDLETOWN, OHIO, A CORPORATION OF OHIO.

METAL ROLLING.

Application filed April 8, 1925. Serial No. 21,661.

My invention relates to plants for the rolling of metal from the ingot into sheets and thin plates and more particularly to a series of successive treatments of a piece of metal, 5 through steps of reduction into the final product.

It is my object to provide a mode of treatment for metal which permits of its reduction in the most economical possible manner, with 10 regularity of product to the desired gauge, and with the minimum of labor cost, machinery upkeep, and time consumed from the ingot to the final product.

In my process I have provided for a treatment of the metal in each stage, which will 15 provide great economy in production, and can route through my rolling and heating elements, an ingot of iron or steel, and reduce it to thin plates, and sheets with a saving in 20 labor at every stage that reduces tremendously the cost of producing sheet metal.

I now have in operation a plant which actually accomplishes the results to be noted by me. Among other things my process results 25 in producing thin sheet and plate metal of definite gauge throughout its length, in avoiding loss of heat, equalizing heat of the piece to the end of obtaining this definite gauge, in the production of a piece which will always easily 30 enter and pass through the successive stands of rolls which engage it, and in the provision of merchantable products, in finished form, at various stages of production, which products may be used in the further steps of the process 35 or sold to the customer after such cold working, or surface treatment as is required.

The terminology in the iron and steel industry has become involved because of specialization in its various branches, so that I 40 do not wish the terminology which is used by me throughout this specification to be taken in too specific a sense.

I accomplish my objects by that certain process of progressive reduction and heat conservation and equalization, to be hereinafter 45 more specifically pointed out and claimed.

In the drawings:

Figures 1, 2 and 3 are continuations in plan view and partially diagrammatic showing a 50 plant for rolling hot metal.

Figure 4 is a continuation on a larger scale showing the plant for reduction of packs to finished gauge.

Figures 1^a, 2^a, 3^a and 4^a are projected side elevations of the mill parts of the plan views, 55 omitting feed tables.

Figure 5 is a vertical section of the pack furnace on same scale as Figure 4.

Figures 6 to 14 are perspectives illustrating 60 the piece in its various stages.

Some of the mechanisms indicated by me are novel with me, and some are old in the art, but I do not desire to cover any specific mechanisms in my present invention, but merely the treatment of hot metal, by means 35 of mechanisms which are within the skill of the person versed in the art to produce and operate by following my directions.

I start with what is known as a slab ingot, indicated at 1, which has greater width than 70 thickness. Among other things my process permits of the use of one size and shape of ingot for all products, which is a considerable economy.

The ingot is first reduced to a slab 2, in a 75 blooming or slabbing mill indicated at 3. The slab will have a cross sectional area which is specified for the production of a given order on the rolling plant. It then passes to a furnace 4 and shear 5.

This furnace, which I have termed an equalizing furnace, operates so as to bring the piece to a proper temperature for the next treatment, and to conserve the heat which still remains in the piece. The shears being at the 85 exit side of the furnace, the time consumed in cutting off the sections at the front end of the piece, does not give the rear end thereof a chance to cool, as it lies within the furnace. It would be required otherwise to cut up the 90 bloom 2 into sections and keep the sections at a soaking temperature until all were uniform, before the next reduction.

The slab is cut into sections 6, which are of 95 a length equal to the desired ultimate width of the finished product, and of the width of the bloom. The pieces 6 are turned at right angles by table 7^a before being passed through the rolls 7, or if the width is suitable for the finished product, there will be no turning of 100

the piece and the length of the piece will be regulated by the quantity of metal desired. The rolls 7 are arranged in tandem, preferably, and the pieces 6 are fed along through these rolls resulting in a thick plate 8 being formed. This plate is then fed through another furnace, and shear device indicated at 9 and 10, resulting in the sheared sections 11, which have uniform heat, uniform shape and uniform cross section for a given run, due to the action of the roll series or "mill" and the action of the furnace and shears.

The pieces 11 are then passed as quickly as possible through a series of stands of rolls 12 and 13. I have indicated pairs of driven rolls at 12, and three high stands of rolls at 13 having the middle roll a small one in diameter, so as to effect rapid reduction. The stands form a mill, which is either tandem or continuous, but preferably continuous, if at all, in the last two stands only. The advantage of having the roll stands in tandem as opposed to continuous, is that it eliminates one factor in apportioning the total required reduction between the various stands, in that drafts may be set to give the best results in shape without regard to elongation of preceding and following stands. For instance any one or more mills may be blanked entirely.

Variable speed motors on each stand of continuous mills partly accomplish this same result, but the adjustment of mill is more complicated.

The composition and original shape of the rolls, the heat of rolls, the draft or amount of screw, and heat of the piece, are best controlled in this mill to the end of providing an active pass between each stand of rolls which is less convex than the convexity of the piece. By active pass I mean the cross sectional area of the space between the rolls while the piece is engaged by them.

The amount the radius of convexity is increased in each stand is subject to limitations of the necessity of keeping up the convexity to the end of the operation, and of preserving a flat piece. An over reduction is likely to extend the center of the piece so much as to result in bulging the piece along the middle and an under reduction to result in "dishing" thereof.

The gradual reduction of convexity of a piece which starts off with sufficient convexity through rolls which are suitably turned, will result in a smooth passage of the piece through every stand of rolls, so that no "dishing" or "twisting" will occur. Also the convexity of piece and active pass results in the piece passing through the center of the rolls and being delivered in true alignment.

The rolls of the mill 12, 13 should be kept cool and very rigidly supported, and the path of the piece through the mill can be very rapid. I run the last stand of rolls at 700 feet per minute in regular practice. I have

shown a water cooling structure at 12^a and 13^a for the rolls of the mill 12, 13, and the housings are very heavy, and of the closed type as distinguished from open.

The finished piece as indicated at 14, may be passed through a roller leveler 14^a, and is then a finished sheet or plate of the jobbing mill type, requiring no more hot working.

Should it be desired to make thin sheets, and of the type product produced on the sheet finishing mills of today, the pieces 14 are matched into packs of two or more as at 15, Figure 12, and reheated in a furnace 16. This furnace is coupled direct with another soaking furnace or equalizing furnace unit 17 and the packs are cut by the shears 18 into the lengths 19 for passage through the sheet mills. It will be observed that the lengthwise components of the metal pieces remain the same throughout all but the blooming mill, in the particular instance being described. The matching may be done after the pieces have passed the furnace 17 and shear 18 instead of before.

By reason of the continuous process above described, and the rapidity of action, it is obvious that I make a great saving in the application of heat to the piece.

The sheet mills are indicated at 20, there being as many stands as desired, four being used by me of which three are shown on my diagram. Located adjacent the delivery sides of the rolls are heating furnaces 21, which heat the packs to desired temperature. The furnaces are far enough away from the succeeding stands of rolls, however, that the operators may watch the pieces and manipulate or manually control their feed into the succeeding mills. The operator can by the control of these furnaces, provide a pack for each pass which has the temperature which he desires. The finished pack is shown at 22.

By forming packs 2, 3, 4 or more of the pieces 14, it will be noted, that I add to the convexity of contour of the packs, over that of the individual pieces making them up. The sheet mills will be so turned, and their screw and temperature and the temperature of the piece, so controlled by the rollers in charge that in the sheet mills, the packs will in each stand be given a reduction along the center, greater than at the edges and the packs held at some convexity of contour up to the last pass. The contour of the packs, by which I mean the periphery of their cross sections, will be such that the ratio of the center thickness to edge thickness will be retained substantially proportionate at each pass, as in the instance of the mill 12, 13.

This as in the other mills of my process insures a smooth passage of the pack through each stand of rolls, and gives a product which is not unduly elongated at the middle or at the side edges, as it passes through each stand. The rolls of mill 20 are run hot, that is to say

they are dry. The packs also are rolled "loose" or "open", that is to say, there is some material placed between the pieces forming the pack to prevent them from sticking, or 5 else after each pass, pieces forming the pack are pulled apart before the next pass.

I find, however, that by the use of the intermediate furnaces, in the sheet reduction steps, I am able to flow water onto the rolls, thus 10 keeping them cold, and operating them as cold mills, the pieces being kept up in temperature intermediate the several stands, when required. Thus I may run the sheet mills "cold" and relieve the roller from the 15 necessity of figuring in a variable temperature factor as to the rolls, in providing for progressive convexities of active pass.

I am not familiar with any process which uses jobbing mill sheets for forming packs 20 for a sheet mill, that is to say, I use material for making packs which is of commercial length and gauge, while all prior practice has been to reduce sheet bars to "rough plates" 25 for making packs, which are of correct length for packs, and are not commercial articles. I am not aware of any continuous process, proposed or adopted, in which there is a cross rolling when the piece is quite thick, but thereafter the piece is kept in a straight line, 30 with its central lengthwise portions preserved as the central lengthwise portions all along. The single cross rolling permits of standard ingot sizes and slab widths for all products which it is desired to produce, shifts 35 the side edges of the slabs to the ends of subsequent pieces and also shifts the pipe in an ingot out of the lengthwise components to the crosswise components of the pieces formed, so that, instead of carrying a defect longitudinally it is restricted to a transverse section 40 permitting the good portions to be used in further steps with the process.

After a piece not already convex has reached a certain stage in its reduction, an 45 effort to set up a convex bite between a stand of rolls operating on the piece, would distort the piece, since there cannot be such a flow of metal during the action of the rolls, as will permit the portions at the edges to be forced 50 into the middle. It is not so important that the piece furnished the mill 12, 13, be specific as to contour, although for any run the thickness should be uniform, since the first stand 55 can set the contours for the remaining stands.

It is of primary importance that the packs furnished the sheet mill are of a known contour for a given run. The fit of the piece as to contours to the active pass between the rolls 60 in the sheet mill, is primary in importance, requiring a caliper of the plates forming the packs so as to give the roller advance information as to subsequent roll action.

An attempt to provide a sheet for con- 65 tinuous rolling, with pieces roughed out from

sheet bars presents several difficulties. In the first place, no satisfactory means has been worked out, so far as I am advised, for the heating, and rapid mechanical and accurate feeding of a piece as short as a sheet bar 70 turned crosswise, similar to the present mill practice of roughing. In the next place the product the ordinary "roughing mill" (so termed) is not a commercial product in itself, and could not be made so because to 75 roll a long piece from sheet bars requires rapid action, to avoid reheating, and a continuous reduction process, neither of which is provided in the roughing mill. Also if the rolls in the mill 12, 13 are not run cold, 80 there will be no practical possibility of control when the operation is very rapid, as is necessary for economy in operation. Instead of cross cutting the jobbing mill sheets in my process and matching them, I may, of course, 85 form doubles by folding over in which instance the sections of the plate are not severed from each other until after doubling.

In the operation of the ordinary sheet mill in several passes, packs are frequently produced which are variously distorted and not flat, and which would be difficult or impossible to handle in a tandem mill. I have accordingly found it to be preferable to maintain a controlled temperature of the pack 90 entering each stand so as among other elements to control a proper temperature of the pack, to result in a flat pack. Thus furnaces are preferably between the several stands, particularly the last few, but difficulties of 95 feeding and requirements for other manipulations of the pack, require that the furnaces do not take up all of the space between the stands, but leave sufficient space for manipulation. 100

Furthermore, due to the necessity of keeping the packs hot they must be kept loose or open in entering each stand, or else they would stick together permanently, and manipulation is required for this purpose. 105

Having thus described my invention, what I claim as new and desire to secure by Letters Patent, is:—

1. That process of reducing ingots to thin plates which consists in forming a slab ingot 115 of a width suitable for the length of a subsequent piece, reducing the ingot to a slab, cross cutting the slab into sections, turning the sections at right angles, and reducing them to plates, cross cutting the plates into sections and reducing the sections in successive stands of rolls to finished thin bodies without subsequent right angled turning after the first one above mentioned. 120

2. That process of reducing metal to thin sheets which consists in providing highly heated plate sections reducing said sections by successively single passes through a series of stands of rolls, maintaining said stands 125 cool, forming packs of cross cuttings of the 130

resulting product of the reduction and reducing said packs by successive single passes through a series of stands of rolls.

3. That process of reducing metal to thin sheets which consists in providing highly heated plate sections reducing said sections by successive single passes through a series of stands of rolls, maintaining said stands cool, forming packs of cross cuttings of the resulting product of the said reduction, and reducing said packs by successive single passes through a series of stands of rolls, which are run hot.

4. That process of reducing metal to thin sheets which consists in providing sections of hot, thick metal, successively reducing said sections by single passes through a series of stands of rolls, maintaining said stands cool, forming packs of the resulting product of the first reduction, and successively reducing said packs by single passes through a series of stands of rolls, which are run hot, the pieces forming said packs being maintained loose with relation to each other, as they enter each pass.

5. That process of reducing metal to thin sheets which consists in providing sections of hot, thick, metal, successively reducing said sections by single passes through a series of stands of rolls, maintaining said stands cool, heating and forming packs of the resulting product of the first reduction, and successively reducing said packs by single passes through a series of stands of rolls, applying heat to the packs between the stands of rolls, the pieces forming said packs being maintained loose with relation to each other, as they enter each pass.

6. A continuous process of sheet rolling which consists in passing a heated pack through successive stands of rolls for single engagement by each stand, passing the pack through a furnace between two at least of said stands, and manipulating the pack to separate the sheets in the open intermediate between the furnace and at least one of the stands between which said furnace lies.

7. That process of reducing plates to thin sheets which consists in passing highly heated plate sections through successive stands of rolls to effect reduction of same to thinness, said thin resulting plates having convexity extending lengthwise thereof, forming a pack of said plates, heating said pack, and reducing the heated pack to thin sheets in successive stands of rolls, said pack being furnished to the steps of reduction into thin sheets as lengthwise sections of the thin plates.

8. That process of reducing metal to thin sheets which consists in providing packs of heated thin metal plates of known contour and having a convexity extending down the middle thereof, and successively passing said packs through individual stands of rolls, hav-

ing a pre-arranged contour with relation to the contour of said packs.

9. That process of reducing metal to thin sheets which consists in providing a pack of heated thin metal plates of known contour, successively passing said pack through single passes between separate rolls, adjusting the temperature of the pack between the stands of rolls and manipulating the pack so that the pieces forming the pack are free of adhesion before entering each pass.

10. That process of reducing metal to thin sheets which consists in providing a series of heated packs of thin metal plates having a predetermined cross sectional convex contour, successively passing said packs through a number of stands of rolls, maintaining the temperature of the packs, and adjusting the rolls of the individual stands so as to elongate the packs equally throughout their width.

11. A continuous process of rolling sheet metal which consists in providing heated ingots, reducing them to long slabs by rolling, cutting crosswise sections of the slabs, reducing the cut sections by continuous passage through successive stands of rolls to long plates, passing the plates through a furnace, and at the exit of the furnace cross cutting the plate into sections of substantial length as distinguished from sheet bars, and passing said sections continuously through successive stands of rolls to reduce them to long thin plates.

12. A continuous process of rolling sheet metal which consists in providing heated ingots, reducing them to long slabs by rolling, cutting crosswise sections of the slabs and turning them at right angles, reducing the cut sections by continuous passage through successive stands of rolls to long plates, passing the plates through a furnace, and at the exit of the furnace cross cutting the plate into sections of substantial length as distinguished from sheet bars, and passing said sections continuously through successive stands of rolls to reduce them to long thin plates, forming packs or doubles of the long thin plates in a way so as to bring their lengthwise components into superimposed position, said packs being additionally heated and sheared transversely, and successively passing said packs through successive stands of rolls to reduce the individual pieces forming the packs to finished gauge.

13. That process of reducing plates to thin sheets which consists in passing highly heated plate sections through successive stands of rolls to effect reduction of same to thinness, said thin resulting plates having a pre-arranged convexity extending lengthwise thereof, forming packs of said plates, heating said packs and reducing them in packs to thin sheets; said packs being furnished to the step of reduction into thin sheets as length-

wise sections of the thin plates so as to result in a greater convexity in the packs than the convexity of the thin plate from which the sections are cut.

5 14. A continuous process of sheet rolling which consists in passing a heated pack through successive stands of rolls for single engagement by each stand, passing the pack

through a furnace between two at least of said stands, and manipulating the pack to separate and align the pieces forming the pack with each other and with the line of feed from stand to stand, in the open intermediate the furnace and at least one of the stands between which the furnace lies.

JOHN B. TYTUS.
